UNITED STATES PATENT OFFICE.

WILLIAM DIETER, OF NEW YORK, N. Y., ASSIGNOR TO E. W. BLISS COMPANY, OF BROOKLYN, NEW YORK, A CORPORATION OF WEST VIRGINIA.

TORPEDO-LAUNCHING TUBE.

1,149,505.

Specification of Letters Patent. Patented Aug. 10, 1915.

Application filed April 20, 1915. Serial No. 22,571.

To all whom it may concern:

Be it known that I, WILLIAM DIETER, a citizen of the United States, residing in the borough of Brooklyn, county of Kings, city 5 and State of New York, have invented certain new and useful Improvements in Torpedo-Launching Tubes, of which the following is a specification.

My invention relates to launching tubes 10 from which submarine torpedoes are projected, and has for its object to provide said tubes with anti-friction devices by which the projection of the torpedoes therefrom may be facilitated.

15 A desirable form in which my invention may be embodied is illustrated in the accompanying drawings wherein,—

Figure 1 is a longitudinal section of a torpedo launching tube equipped with my invention partly broken. Fig. 2 is a cross section on the line 2—2 Fig. 1. Fig. 3 is a detail end view of one of the housings for my invention and associated parts. Fig. 4 is a similar view with the yoke removed; 25 and Fig. 5 is a cross section on the lines 5—5 Fig. 2.

My invention is illustrated as applied to a torpedo launching tube A which as to its general construction is of a known type and 30 is provided with a compressed air tank B and the usual sighting glass C. The body a wherein the torpedo is held before launching is separated from the spoon a¹ by a gas check a² and the tube has a pivot a³ mounted upon a suitable rotary standard a⁴ which 35 rotates upon the base a⁵ and is borne thereon by anti-friction devices. The spoon a¹ is broken for convenience of illustration.

According to my invention an anti-friction device D is provided for the purpose 40 of facilitating the launching of the torpedo and this is mounted within the body a so that the upper surface thereof shall receive the weight of the torpedo and enable the 45 same to leave the launching tube without friction. I have illustrated the said anti-friction device as being contained upon the lower surface of the tube in which position it supports the torpedo during launching 50 and eases its passage through the tube. Preferably a series of such anti-friction devices are employed and I prefer to place the same on both sides of the pivot a³ as shown at D¹ whereby the tail of the torpedo is

supported until it has completely left the 55 tube.

Each anti-friction device D is preferably situated within a housing E which forms an extension of the torpedo tube and in the form shown where the inner part of said 60 housing communicates freely with the body of the tube a, the housing is made fluid pressure tight so that none of the fluid pressure employed to launch the torpedo shall leak through the housing. This is of 65 greater importance for the housings which lie at the rear of the gas check a² than for those situated beyond the gas check.

The form of anti-friction device D which I prefer to employ is a roller, the outer or 70 bearing surface of which I prefer to make of a shape substantially conforming to the exterior surface of the torpedo and as these are cylindrical, said surface is illustrated as concave axially. Such form of roller acts 75 to guide the torpedo during launching. The rollers D are mounted upon spindles H upon which they may revolve or which may revolve with the said rollers. I prefer to mount the said rollers to revolve upon their 80 respective spindles. These spindles have suitable bearings at their ends illustrated as bushings I. These bushings are provided for each end of the spindle and are maintained in position by removable yokes J 85 likewise situated at each end and which are provided with bolts j whereby they are secured to a fixed part of the housing E. The bushings I are mounted in openings B² in the ends of the housings E and each of the 90 said bushings is illustrated as having an annular peripheral channel i which may, if desired, receive a packing to prevent leakage of fluid pressure.

In the practical employment of my invention it is highly desirable that the anti-friction devices D should be capable of adjustment so that their bearing surfaces may be brought to correct position to properly support the torpedo G and whereby the 95 clearance of the torpedo may be varied. Such adjustment is relatively very slight and is useful because in the ordinary process of manufacture the extremely slight projection of the bearing surface above the bottom of the tube would not always be obtained with the desired accuracy. It is also 100 highly desirable in the case of the particular

anti-friction devices illustrated, the roller D, that each end of this roller should be made adjustable and that the adjustments for each end should be the same.

5 A desirable method of attaining this adjustment is that illustrated wherein the bearings I¹ for the roller spindle II in the bushing I are made eccentric by being bored off center, and I have found that a sufficient 10 adjustment may be obtained by producing the said boring about one-eighth inch off center. The eccentric bushings I are revolute in their bearings B² and as they are turned the anti-friction rollers D are correspondingly raised and lowered. Means are provided for gaging the extent of adjustment imparted to the rollers D and for locking the bushings in adjusted position and such means comprise a series of holes 15 K with which each bushing is provided on its outer end surface, and these holes as the bushing is turned one way or the other are brought to register with a corresponding hole K¹ in a normally stationary part, as 20 for instance in the yoke J, and the bushing is held in adjusted position by a pin L which passes through both of the holes. As illustrated the pin L is screw-threaded into the hole K¹ in the yoke and is adapted to enter 25 any of the corresponding holes K in the bushing which may be in alinement. Each 30 of the bushings is equipped with a similar series of perforations K, and these are correspondingly placed in the said bushings, 35 and to insure accuracy of adjustment of the two ends of the roller D each of the holes in the said series K is correspondingly numbered. Arrows are provided which indicate 40 the direction of rotation of the bushing to attain the desired adjustment. A lubricating cup M is provided through which lubricating material is introduced and which passes through an axial channel h in the spindle II and thence through radial passages h¹ to the bearings. A passage i¹ is 45 provided with leads to the channel i.

The bushings I are illustrated as provided with annular flanges i² which over-hang the walls of the housing bearing B² and provide 50 stops for the accurate adjustment of the said bushings. The roller spindles H are likewise provided with annular shoulders h² which are adapted to bear against the inner edges of the bushings I.

55 Each housing 2 is preferably provided with drainage openings d at a lower part thereof and which are closed by suitable plugs against leakage of pressure.

I have illustrated six anti-friction devices 60 D within the pivot a³ of the launching tube and one device outside of the pivot, but the number of such devices is not material and more or less thereof may be employed, or they may be differently arranged. Further- 65 more the precise construction of anti-fric-

tion devices illustrated, although this is the best known to me, is not the only form in which my invention could be embodied, and although I have illustrated such device as being made adjustable this adjustable feature might be dispensed with by a nice relation of the parts in manufacture. These and other modifications may be made in my invention within the limits of the appended claims without departing from the essential 75 spirit of the invention as set forth in such claims.

What I claim is:—

1. A torpedo launching tube, and anti-friction launching rollers therein having concave surfaces and devices for adjusting said rollers relative to a torpedo in said tube. 80
2. A torpedo launching tube and anti-friction launching rollers therein having concave surfaces. 85

3. A torpedo launching tube, and anti-friction launching rollers therein having concave surfaces and devices for vertically adjusting each end of each of said rollers. 90

4. A torpedo launching tube, and anti-friction launching rollers therein having concave surfaces, a spindle for each of said rollers, bearings for each end of said spindle and means for adjusting each of said bearings. 95

5. A torpedo launching tube having a series of fluid tight housings disposed throughout the lower surface thereof and on both sides of the pivotal mounting of said tube and anti-friction devices rotatably mounted therein. 100

6. A torpedo launching tube, anti-friction launching rollers therein, a spindle for said rollers, eccentric revolute bushings for each end of said spindle and locking devices for said bushings. 105

7. A torpedo launching tube, anti-friction launching rollers therein, a spindle for said rollers, eccentric revolute bushings for each end of said spindle, adjusting gages at each end of said bushing for obtaining corresponding adjustments and a lock for each end of said bushing. 110

8. A torpedo launching tube, anti-friction launching rollers therein, a spindle for said rollers, eccentric revolute bushings for each end of said spindle, each bushing having a series of corresponding spaced perforations and a locking pin mounted in a fixed part at each end of said bushing to have longitudinal movement and adapted to enter either of said perforations. 115

9. A torpedo launching tube, anti-friction launching rollers therein with concave surfaces, a spindle upon which said rollers turn, bushings at each end of said spindle, each bushing having a series of corresponding spaced bolt holes, a locking bolt mounted in a fixed part and adapted to enter either of said bolt holes. 125
130

10. A torpedo tube, a revolute anti-friction device therein, a spindle therefor, eccentric revolute bushings for each end of said spindle, a yoke at each end of said bushings and locking devices associated with each yoke for engaging said bushing at spaced and identified intervals for obtaining a simultaneous adjustment of all parts of said anti-friction devices relative to a torpedo in said tube.

11. A torpedo tube, revolute rollers therein, bearing surfaces substantially conforming to the torpedo, a spindle therefor upon which said rollers turn, revolute eccentric bushings for said rollers, yokes for each of said bushings, each bushing having an annular series of correspondingly spaced and identified bolt holes, a locking bolt threaded in each yoke and adapted to enter either of said bolt holes in its respective bushing.

12. A torpedo launching tube, rollers at

the lower parts adapted to engage and support the torpedo and ease its passage through the tube, and means for adjusting 25 said rollers vertically adapted to vary the clearance of the torpedo.

13. A torpedo launching tube, rollers at the lower parts adapted to engage and support the torpedo and ease its passage 30 through the tube, and means for adjusting each end of said rollers vertically adapted to vary the clearance of the torpedo.

14. A torpedo launching tube having anti-friction launching rollers on both sides of 35 the pivot.

In witness whereof, I have hereunto signed my name in the presence of two subscribing witnesses.

WILLIAM DIETER.
